ROTATABLE HONE

Henry Robert Billeter, Deerfield, and Walter P. Kushmuk, Chicago, Ill., assignors to Ammco Tools, Inc., North Chicago, Ill., a corporation of Illinois

Application May 17, 1955, Serial No. 508,928

10 Claims. (Cl. 51—184.3)

The present invention relates to rotatable cylinder hones and more particularly hones suitable for honing small bore cylinders, such as brake cylinders, piston pin holes and the like.

The hone of the invention is of the general character that includes a body with a plurality of abrasive units mounted thereon and adjustably movable in directions for expanding and contracting the hone in radial directions.

An object of the invention is to provide an improved hone of the foregoing character.

Another object is to provide, in a hone of the foregoing character, improved construction including a body and abrasive units quickly and easily attachable to the body and detachable therefrom.

A still further and more specific object is to provide, in a hone of the character just noted, yieldable detent means in the body for normally retaining the abrasive units thereon against their being accidentally displaced but permitting their easy removal by application of deliberate manual force.

Another object is to provide a simple and rugged means for retaining the abrasive units on the body enabling their removal therefrom merely by the simple manipulation of over-expanding the units.

Another object is to provide novel adjusting means in a hone of the above general character that is unusually simple, rugged and inexpensive.

Other objects and advantages of the invention will appear from the following detail description taken in conjunction with the accompanying drawings in which:

Figure 1 is a side elevational view of a hone embodying the invention, showing the abrasive units in partially expanded position;

Figure 2 is an enlarged fragmentary elevational view of a portion of the hone of Figure 1, showing the abrasive units in a somewhat expanded position;

Figure 3 is a sectional view, on an enlarged scale, taken on line 3—3 of Figure 1;

Figure 4 is a sectional view taken on line 4—4 of Figure 2;

Figure 5 is a longitudinal sectional view taken on line 5—5 of Figure 2;

Figure 6 is a sectional view taken on line 6—6 of Figure 5;

Figure 7 is a sectional view taken on line 7—7 of Figure 5;

Figure 8 is a sectional view taken on line 8—8 of Figure 5;

Figure 9 is a perspective view of the clip interconnecting the abrasive units and the expanding knob;

Figure 10 is an enlarged sectional view taken on line 10—10 of Figure 1;

Figure 11 is an elevational view of a modified form of hone;

Figure 12 is a longitudinal sectional view taken on line 12—12 of Figure 11;

2

Figure 13 is an end view from the left of Figure 11; and

Figure 14 is a side elevational view of one of the abrasive units of the form of Figures 11—13.

In the form shown in Figures 1 to 10 which embodies the principles of the present invention, the hone includes a honing head 12 made up of a pair of abrasive units 14 mounted for expansion and contraction on a central supporting shaft 16. The shaft 16 includes a body portion 18 supporting the abrasive units 14, a shank portion 20, preferably cylindrical and constituting the means by which the hone is mounted in a driving device and, at the end opposite the shank 20, a stem 22 on which an expansion knob 24 is adjustably mounted for expanding and contracting the abrasive units. The manner of expanding the units will be described fully hereinafter. The shank 20 is mounted in a suitable manner in a known type of driving means (not shown) for rotating the hone, the abrasive units 14 being rotated with the shaft 16 for performing the surfacing operation.

A known type of centering cone 26 is preferably included in the device, being slidably mounted on the shank 20 for the usual purpose, namely, that when the device is used, for example, in honing a piston pin bore or bearing, the head 12 is disposed in one portion of the bore and the centering cone held to the opposite and aligned portion, whereby the hone is properly aligned with the axis of the two bore portions.

The body portion 18, as shown particularly in Figures 3, 4 and 10, is polygonal (preferably hexagonal) in cross section, and particularly it has oppositely disposed, parallel side bearing surfaces 28 against which certain side portions of the abrasive units 14 are disposed and effectively retained for rotation of the abrasive units in response to rotation of the body portion 18.

The abrasive units 14 referred to above are arranged for expansion and contraction movements on the body portion 18 and these movements are produced by a camming action. The elements for effecting such action are mounted on the abrasive units and on the body portion 18. Those preferably include a plurality of pins 30 fitted in apertures in the body portion 18 and projecting from the opposite side bearing surfaces 28 mentioned. The pins 30 may be secured in any desired manner, as by a press fit, and are spaced at suitable intervals, preferably uniform intervals, being of a sufficient number (e. g. four) to provide adequate support for the abrasive units according to the length of the latter, for imparting the desired stability to the unit.

The abrasive units 14, identical in shape, each includes a channel shaped carrier 42 and a plurality of abrasive elements or "stones" 44 mounted thereon. Each channel 42 includes a web portion 46 and side flanges 54 and 56, with cam surfaces 60 positioned to engage the cam pins 30 respectively. The cam pins 30 and surfaces 60 effect expansion of the units in a manner to be described fully hereinafter. The web portion 46 or "roof" has transversely angled portions corresponding generally in arrangement with the polygonal surfaces of the body portion 18. The two angularly disposed side portions 48 of the web are so arranged that the abrasive elements 44 thereon are disposed at approximately 60° apart as explained more in detail in the copending application of Henry Robert Billeter, Serial No. 497,128, filed March 28, 1955. The abrasive elements or stones extend the full length of the carriers, and hence substantially of the body portion, and are secured in position in a suitable manner as by a cement.

The channel construction (see Fig. 10) forms wide side ridges 50 and reverse bend portions 52 which merge into the side flanges 54 and 56. The side flanges are positioned in overlying relation to the side bearing surfaces

28 of the body portion 18 and are supported by those side surfaces, either directly or indirectly, i. e., the two flanges of either channel carrier do not both bear directly on those surfaces but one of the flanges of each carrier bears directly on the corresponding surface while the other is disposed outwardly of the adjacent flange of the other carrier and bears against the latter. The arrangement is shown best in Figure 10. The flange 56 (right hand flange as viewed in Fig. 10) of the upper carrier bears directly on the side surface 28 at one side of the body portion 18, while the flange on the opposite side of the body portion which bears directly on the opposite side surface 28 is the corresponding flange 56 of the lower carrier 42. Likewise the flange 54 on that side (left hand side) of the device is disposed outwardly of the flange 56 of the lower carrier. The flanges on the two carriers overlap at all times. In fully or nearly fully expanded position (Fig. 8) they extend past the central transverse plane, and in collapsed position they overlap or overlie one another substantially completely (in vertical direction, as shown for example in Fig. 10).

The inner flange 56 of each carrier which directly engages the corresponding side bearing surface 28 of the body portion 18 is provided with a slot 58 for receiving a corresponding detent ball 34, of detent means, for releasably retaining the abrasive units on the body portion. The detent means, forming an important feature of the invention, is indicated in its entirety at 32 (see Fig. 10) and preferably takes the form of a pair of such detent balls 34 disposed in a transverse bore 36 in the body portion and opening through the side bearing surfaces 28. The bore 36 is parallel with the bores in which the cam pins 30 are mounted. The balls 34 are urged outwardly by a compression spring 38 confined between the two balls, and retained in the bore by inwardly directed portions 40, formed as by peening, at the ends of the bore. The dimensions of the bore and balls are such, as shown in Fig. 10, that the balls project out of the bore a distance sufficient to enter the slots 58 in the flanges 56 and produce a retaining effect on the abrasive units.

The slots 58 are arranged in positions inclined to the longitudinal axis of the hone, as shown in Figure 1, so as to enable constant engagement of the detent balls 34 in those slots in response to the movement of the abrasive unit in expanding and contracting directions. The slots 58 on opposite sides of the hone are disposed oppositely, corresponding to the direction of movement of the respective abrasive units.

The arrangement of the flanges 54 and 56 with respect to the body portion 18 results in a staggered relation, i. e., in progressing transversely through the device, as oriented in Figure 10, the flanges considered serially are alternately opposite with respect to the two abrasive units, and any tendency to cock or rotate the abrasive units about the axis of rotation is effectively countered by this staggered relation. For example, considering the direction of rotation as clockwise (Fig. 10) as indicated by the arrow 59, the top unit or carrier would tend to be cocked or rocked counterclockwise relative to the body portion 18. Any such relative cocking or rocking would tend to spread the flanges of that carrier upon engagement with the corners of the body portion between adjacent surfaces. However, because the flange 54 on the bottom carrier is disposed outwardly of the adjacent flange 56 of the upper carrier, the tendency of the flange 56 to spread is checked by the flange 54 in engagement with it and also by the detent. Such spreading action would result in springing out of the lower edge of the flange 56 but this lower edge is adjacent to the return bend portion 52 of the lower carrier which, in turn, is close to the web portion of that carrier, so that a mechanical advantage relative to the flange 56 is established because the reaction is exerted against the lower edge of the flange 56 which would have the greater swinging movement, and accordingly re-

sists the tendency to the spreading action. The same effect is produced on both sides of the hone. The carriers 42 may have a limited degree of resiliency since they are stampings but from a practical standpoint the resiliency is not substantial. The shape of the return bend portions 52 on opposite sides of a channel are of different angular directions because of the staggered relation, i. e., the portion 52 connected with the flange 56 is disposed at a smaller angle to the flange than the opposite portion because the flange 56 is innermost with respect to the proximate flange 54. The arrangement, however, is symmetrical in this respect around the hone.

The cam surfaces 60 corresponding to and engageable with the respective cam pins 30 on the body are arranged so that the two cam surfaces on the two flanges of the carriers that engage one end of a cam pin are disposed at opposite angles. The expansion and contraction movements of the abrasive units, as was pointed out above, is produced by longitudinal movement thereof, and this movement acting through the camming elements produces the radial expansion and contraction movements. The resulting movement therefore is in a direction inclined to the axis of the hone. Hence the slots 58 being at the same angle as the corresponding cam surfaces 60 enables the abrasive units to be moved while the detent balls 34 remain in fixed relation longitudinally of the hone. The expansion knob 24 serves to positively expand the abrasive units as well as to positively contract them. The connection between the expansion knob and the abrasive units takes the form of a detachable clip 62 (shown particularly in Fig. 9) preferably of unitary form, as provided by a stamping formed preferably of spring material, and includes a central U-shaped portion 64 and side leg portions 66 which merge into longitudinally extending arms 68 which, in turn, terminate in outturned ears 70. The clip 62 is positioned in the hone on the body portion 18 between the expansion knob 24 and the abrasive units 14. For this purpose the body portion has a reduced portion 72 (Fig. 7) on which the side legs 66 resiliently but firmly bear.

The reduced portion 72 of the body portion extends transversely a sufficient distance that the longitudinally extending arms 68 of the clip 62 are disposed on opposite sides of the body portion 18, and the outturned ears 70 are disposed respectively in the slots 74 in the carriers 42 and in a circular cavity 76 in the expansion knob 24. Each flange in each carrier has a slot 74 which opens through the respective side edge of the flange (Fig. 2), and the slots in the two flanges on each side form a single slot with closed ends into which the outturned ears 70 project. The expansion and contraction of the abrasive units results in lengthening or shortening of the close-end slots, and their longitudinal dimension, when shortened, is greater than the transverse dimension of the ears 70. The reduced portion 72 of the body portion is of appropriate length (Fig. 5) for accommodating the clip in the longitudinal movement of the latter in the expanding and contracting movements of the hone.

The insertion of the ears 70 at the opposite end of the clip into the circular cavity 76 in the expansion knob 24 may be accomplished before the expansion knob is threaded onto the stem 22, by springing of the ends of the arms 68 inwardly toward each other, and thereafter the expansion knob is turned up to a position approximating that of Figure 5, and the carriers 42 are then fitted on the body by their being snapped over the detent balls, the open end of the slots 74 in the carriers receiving the ears 70 and accommodating such movement of the carriers.

The expansion knob 24 has an end opening 78 for receiving the stem and this is of appropriate diameter to also receive the arm portions 68 of the clip when the clip is mounted on the stem or body portion 18. The ears 70 extend into the circular cavity 76 which is of greater diameter than the end aperture 78, the cavity having axial-78 ly directed and opposed faces 80 and 82 for engaging the

ears 70 on respectively opposite sides for moving the clip in longitudinal directions. The axial dimension of this cavity is greater than that of the ears to provide a limited amount of play therebetween. A collar 84 is slidably mounted in bore 86 of the expansion knob and urged outwardly by a compression spring 88 in the bore into yielding engagement with the end of the clip.

The hone is of pre-set type, the expansion of the abrasive units being accomplished by adjustment of the expansion knob 24. The knob is rotated in a direction to cause it to advance inwardly (to the right as viewed in Fig. 1) for expanding the units, this action forcing the clip 62 in an inward direction and hence the units in the same direction. This longitudinal or axial movement of the units effects a corresponding action of the camming elements 30 and 60 and produces radial expansion of the units. For a honing or surfacing operation, the units are expanded for bringing the abrasive elements into firm engagement with the cylinder surface being treated, and as the operation continues, the spring 88 produces continued yieldable expanding pressure on the units.

The expansion knob is turned in the opposite direction to contract the units. This movement of the knob moves the abrasive units in that direction longitudinally, and, in response thereto, the detent balls 34, acting in the inclined slots 58 move the abrasive units radially inwardly.

The detent means 32 serves as a very simple and effective means for retaining the abrasive units on the body portion, and facilitating placing the units thereon and removing them therefrom. To place the units on the body, the flanges of the carriers are fitted to the opposite sides of the body portion and simply forced over the balls 34, permitting the balls to snap into the slot 58. The open-face character of the cam surfaces 60 facilitates fitting the units to the body member by such simple movements. The units are removed in as simple a manner, in a reverse movement. The detent means thus serves the dual purpose of releasably retaining the carriers on the body portion and camming the carriers inwardly in contracting direction.

The hone is of unusually simple and rugged construction throughout, with little likelihood of losing accuracy between the various elements thereof.

The second embodiment of the hone, illustrated in Figs. 11 to 14, is somewhat similar to the hone of the first embodiment but includes a different form of means for contracting the abrasive units. The present hone is of the type for use in a honing machine (not shown) although the principles of this form of the invention are equally applicable to the set-up type of hone of the first embodiment.

The hone of Figs. 11 to 14 includes a honing head designated generally at 91, and a tubular drive shaft 92 adapted for mounting in a honing machine for rotation about its longitudinal axis by suitable operating means in the honing machine. A body 94 is mounted in the drive shaft for rotation therewith, by suitable means, such as by a screw-threaded connection 96 including threads in the inner surface of the drive shaft and on a reduced extension 98 on the body.

The tubular drive shaft 92 includes an actuating rod or plunger 100 mounted for axial sliding movement therein, under suitable control of the honing machine in which the hone is mounted, this operating mechanism being well known. The actuating rod 100 is effective for expanding and contracting the abrasive units 102 in response to the longitudinal sliding movement of the rod, as will be brought out more fully hereinafter.

The body 94 is preferably polygonal in cross section (Fig. 13) and has diametrically opposite bearing surfaces 104 similar to the hone of the previous embodiment. Expanding cam pins 106 are secured in the body and arranged with their end portions extending through the surfaces 104, as shown best in Fig. 12. In the present instance the honing head 91 is rather short and two such

expanding cam pins 106 are sufficient for producing the expanding movement. A contracting cam pin 108 is also mounted in the body and similarly arranged with its end portions projecting through the opposite side bearing surfaces 104, being preferably disposed between the expanding cam pins 106. These pins may be secured in the body in a suitable manner such as by a press fit.

The abrasive units 102 are two in number as in the first embodiment and are arranged on opposite sides of the body 94. The units 102 are identical in construction and shape, and each includes a channel shaped carrier 109 having a web 110 and side flanges 112 and 114. The web 110 has inclined side portions 116 on which the abrasive elements or "stones" 118 are mounted, the latter extending a suitable distance longitudinally of the carriers in accordance with the intended dimension of the effective portion of the honing head, as shown in Figs. 11 and 12. The units are arranged with their flanges in staggered relation as in the previous embodiment, the side flanges 112 and 114 of the two units being in alternate overlying relationship. The flanges 114 of the two units directly engage the respective side bearing surfaces of the body and the flanges 112 engage the outer surfaces of flanges 114 (Fig. 13). Thus, progressing in direction transversely through the head, as oriented in Fig. 13, all of the flanges taken in the aggregate are alternately arranged; that is, each unit has one flange directly engaging the corresponding bearing surface of the body and its other flange directly engaging the corresponding inner flange of the other unit. The flange 114 is of lesser depth than the flange 112, enabling the units to be contracted a maximum extent (Fig. 13) while enabling the outer flange 112 in each case to overlie the proximate flange 114 to a maximum extent.

Each flange 112, 114 includes three camming surfaces for engagement respectively with the three cam pins 106, 106 and 108. These cam surfaces are most clearly shown in Fig. 14 which illustrates one of the abrasive units detached from the hone, in side elevational view, and with the flange 114 presented to the observer. The cam surfaces include two expanding cam surfaces 120 which engage the expanding cam pins 106, and a contracting cam surface 122 which engages the contracting cam pin 108. The expanding cam surfaces 120 and the contracting cam surface 122 are parallel, and spaced apart, as shown, with the contracting surface 122 intermediate the two expanding surfaces.

The flanges 112, 114 are provided with open-ended slots 124 adjacent one end for reception of the out-turned ends 126 of the legs 128 of a forklike clip or actuating connector 130. The legs 128 are interconnected by an end piece 132 having an aperture receiving extension 134 on the end of the rod 100. A compression spring 136 surrounds the reduced extension 134 and is compressed between the end piece 132 and the inner end of a bore 138 formed in the reduced extension 98 of the body. The body is provided with grooves 140 for receiving the legs of the clip 130, the grooves being of appropriate width for slidingly receiving the latter without undue side play.

The clip 130 constitutes the means transmitting to the abrasive units the movement of the rod 100 longitudinally for expanding and retracting the units, the clip being moved in expanding direction (to the right, as viewed in Figs. 11 and 12) by the rod 100, and in the opposite and contracting direction by the spring 136. Upon movement of the clip 130 in expanding direction, and consequent movement of the units in that direction, the cam surfaces 120 ride up on the cam pins 106, causing the abrasive units to expand in radial direction. Since the cam surfaces 122 have the same slope as the surfaces 120, the expanding movement is effected without interference by the pin 108. Upon movement of the clip 130 in the opposite direction (to the left as viewed in Fig. 11) the abrasive units are drawn longitudinally in that direction, and the contracting cam surfaces 122,

acting on the cam pin 108, move the abrasive units radially inwardly in contracting direction. During movement in each direction the outturned ends 126 have sliding movement in the slots 124 which are of sufficient depth to permit the units to contract fully without the ends of the closed slots engaging the ends 126.

It will be appreciated that although only a single cam pin 108 for the contracting function is provided, the abrasive units are readily moved bodily in the contracting movement without rocking about the axis of the pin 108, since any tendency to such rocking action is counteracted by one or the other of the two expanding cam pins 106.

The cam surfaces 120, 122 are open-ended, i. e., the slots forming the surfaces receive the respective pins 106, 108 in response to inward movement of the units. Thus the units may be applied to or removed from the body merely by their being fitted to the body in lateral movement. This is done when the hone is in "over-expanded" condition with the clip 130 projected to a position beyond normal fully expanded position. When the units are on the body, the projection of the clip to such conditions causes the cam surfaces 120 to ride up on the cam pins 106 sufficiently to enable the cam surfaces 122 to ride free of the cam pin 108. The operator then merely lifts the units from the body. To attach the units to the body, a reverse succession of the steps is followed, i. e., the clip is moved to over-expanded position, and the units fitted to the body with the slots 124 receiving the outturned ends 126, and the clip is retracted, whereupon the units are drawn longitudinally with the cam surfaces 122 engaging under the respective ends of the cam pin 108, the latter action contracting the units radially inwardly.

The present construction provides an unusually rigid arrangement for camming the abrasive units in both expanding and contracting directions. There is a minimum of parts or elements susceptible of becoming worn or defective. The retention of the units on the hone body is positive in all normal conditions. The units can be attached and detached by unusually simple manipulations.

We claim:

1. A rotatable hone comprising a body having means for connection with driving means, a plurality of abrasive units mounted on the body together having a plurality of longitudinally extending abrasive elements distributed around the hone and each unit having portions disposed on diametrically opposite sides of the body, detent means in the body yieldingly biased outwardly in directions perpendicular to the side portions of the units and into openings therein for releasably retaining the units on the body, the units being releasable in response to movement thereof in the planes of the side portions, cam surfaces on said side portions of said abrasive units, and rigid pins extending from said body, said body being longitudinally movable with respect to said abrasive units whereby said cam surfaces cooperating with said cam pins and said detent means may positively move said abrasive units radially outwardly and inwardly.

2. A rotatable hone comprising a body having means for connection with driving means, a plurality of abrasive units mounted on the body together having a plurality of longitudinally extending abrasive elements distributed around the hone and each unit having lateral flanges for releasably retaining the units on the body, spring pressed detent balls urged into openings in the flanges for releasably retaining the units on the body, and means for expanding and contracting the units radially.

3. A rotatable hone comprising a body having means for connection with driving means, a plurality of abrasive units mounted on the body together having a plurality of longitudinally extending abrasive elements distributed around the hone and each having lateral flanges respectively on opposite sides of the body, the flanges of the units overlapping and the flanges being alternately disposed as between units and considered in transverse direc-

tions so that only one flange of each unit is proximate the body, a pair of detent balls in the body spring-pressed outwardly oppositely into holes in the respective ones of said proximate flanges, and means for expanding and contracting the abrasive units radially.

4. A rotatable hone comprising an elongated body having means for connection with driving means, a pair of elongated abrasive units each including a channel shaped carrier having a web and side flanges and each having an abrasive element on the outer surface of the web, the units being mounted on the body with the flanges of each unit on opposite sides of the body, spring pressed detent means in the body retractably projecting into holes in the flanges for releasably retaining the units on the body, the flanges and body having cam elements operatively interengageable for expanding the units radially in response to longitudinal movement thereof, and means on the body for moving the units longitudinally, said holes being inclined complementally to the cam elements in the respective flanges whereby to enable the longitudinal and radial movement of the units with the detent means remaining stationary.

5. A rotatable hone comprising a body, a plurality of axially spaced cam pins in the body projecting from diametrically opposite sides thereof, a pair of abrasive units mounted on the body each including a channel shaped carrier having side flanges disposed on opposite sides of the body and the flanges having cam surfaces respectively engaging the pins and operative therewith for expanding the units radially in response to axial movement thereof, means mounted on the body for so moving the units axially, and spring pressed detent balls in the body biased into slots in the flanges for releasably retaining the units on the body, the slots being inclined complementally to the cam surfaces in the respective flanges whereby to enable the axial and radial movement of the units with the detent balls remaining translationally stationary.

6. A rotatable hone comprising a body, a plurality of abrasive units detachably mounted on the body for movement longitudinally, said body having a threaded extension on one end, an expansion knob threadedly mounted on the extension, and a U-shape clip detachably mounted on the body effectively between the units and expansion knob and having axially extending arms on opposite sides of the body with outturned ears on the extremities of the arms, the units having transverse slots receiving the ears on the clip at the respectively adjacent ends, and the expansion knob having a circular cavity receiving the ears at the other end, the cavity having axially and oppositely directed faces for engaging the ears in both directions of axial movement.

7. A rotatable hone comprising a body, a plurality of abrasive units detachably mounted on the body for movement longitudinally and radially, cam means between the body and abrasive units for radially expanding and contracting the units in response to movement thereof longitudinally, the units including channels each with flanges on opposite sides of the body arranged with the flanges on the several units overlapping, said body having a threaded extension on one end, an expansion knob threadedly mounted on the extension, and a U-shaped clip detachably mounted on the body effectively between the units and expansion knob and having axially extending arms on opposite sides of the body with outturned ears on the extremities of the arms, each flange having a slot opening through the edge of the flange and arranged so that in the overlapping flanges a closed-end slot is formed in two flanges, the slots being disposed transversely and positioned at the end adjacent the clip, said slots receiving the ears on the clip at the respectively adjacent ends, and the expansion knob having a circular cavity receiving the ears at the other end of the clip, the cavity having axially and oppositely directed faces for engaging the ears in both directions of axial movement

and spaced apart to provide for limited play between the knob and clip, and spring means in the knob biasing the clip and thereby the units axially in expanding direction.

8. A rotatable hone comprising a body, a plurality of abrasive units detachably mounted on the body for axial and radial movement, first cam means on the body, cam means on the units engageable with the said first cam means and effective for expanding the units in radial direction in response to movement in one longitudinal direction, second cam means on the body, cam means on the units engageable with the said second cam means and effective for contracting the units in radial direction in response to movement in the opposite longitudinal direction, said cam means being open-ended enabling separation of the units from the body by radial outward movement, and actuating means on the body engaging the units for moving them in longitudinal directions.

9. The invention as set forth in claim 8 in which the first and second cam means on the body consist of pins having end portions projecting out opposite side surfaces of the body, and the cam means on the units consist of inclined surfaces in side portions of the units proximate the said side surfaces of the body.

10. A rotatable hone comprising a body, a tubular drive shaft mounting the body and constituting means for mounting the hone for rotation, said body having diametrically opposite side bearing surfaces, a first and a second cam pin mounted in the body with end portions projecting outwardly from said side surfaces, a pair of abrasive units detachably mounted on the body each including side flanges overlying said side surfaces of the body, said side flanges each having parallel but oppositely facing cam surfaces respectively engaging said first and second cam pins and operative for expanding and contracting the units in radial directions in response to movement in longitudinal directions respectively, an actuating rod slidably mounted in the tubular shaft, and clip means interconnecting the rod and the units for moving the latter longitudinally.
